Application November 15, 1933, Serial No. 698,109

14 Claims. (Cl. 198—219)

My invention relates generally to heating furnaces, and more particularly to heating furnaces used for metallurgical purposes and through which the material to be treated is conveyed at such a rate of travel, with reference to the length of the furnace chamber and the heat supplied, as to enable the articles to be properly heated by the time they shall have reached the delivery or discharge end of the furnace. The particular type of heating furnace of this character to which my invention relates is generally known as a "walking beam" type furnace; that is, a furnace wherein reciprocating members which cooperate with either stationary supports or other reciprocating members are used for transporting material through the furnace.

In furnaces of this character considerable difficulty has been encountered in providing satisfactory means for conveying the material through the furnace, which will not be deleteriously effected by the heat of the furnace. The temperatures in furnaces of this character are generally rather high, ranging up to approximately 1950° F. in certain types thereof. Consequently, it is necessary to provide material transporting means which is of such character as to not buckle, warp or twist from the action of the heat to which it is subjected. The use of alloy beams for the material supporting and conveying mechanism has been proposed, but the use of alloys in furnace structures known in the art at the present time involves an addition of a very appreciable amount to the cost thereof.

By my invention, I provide an improved furnace construction of the character above referred to, embodying novel material supporting and conveying mechanism. The material supporting and conveying mechanism which I provide is of such character as to prevent buckling, twisting, or warping of the parts thereof, which are subjected to the high temperatures of furnaces of the character referred to. It is also of such character as to permit the use of alloys in the structure without unreasonably increasing the initial cost thereof over the cost of furnaces of this character wherein the material supporting and conveying mechanism is made of ordinary steel.

In accordance with my invention, I further provide novel means carried by the material supporting beams on which the material rests during its passage through the furnace and which is so arranged as to afford adequate support for the material at all times and prevent bending thereof.

By my invention, I further provide novel mechanism for removing the material from the furnace at the discharge end thereof, the operation of which is synchronized with the operation of the conveying mechanism.

The advantages of my invention will be apparent to those skilled in the art as the nature of the invention is better understood. It consists in the novel construction, combination and arrangement of parts hereinafter more fully described, illustrated and claimed.

In the drawings I have shown a preferred embodiment of my invention and several modifications thereof. It will be understood, however, that I do not intend to be limited to the structures shown in the drawings, as my invention may be otherwise embodied. In the drawings my invention is shown as applied to a pack heating furnace. It will be understood by those skilled in the art to which this invention appertains that my invention is equally applicable to other types of heating furnaces, for instance, the so-called "normalizing" furnaces.

In the drawings:—

Figure 18 is a fragmentary vertical sectional 25 view of the apparatus shown in Figure 16 and showing the manner in which the beams are supported in the furnace;

30 Figure 19 shows the manner in which the beams in the embodiment shown in Figure 16 are supported and maintained in alignment at the intermediate supporting piers; and

35 Figure 20 is a plan view of the cap on which the horizontally movable beams are mounted on the intermediate supporting piers.

35 The embodiment of my invention shown in Figures 1 to 7, inclusive, and 11 to 13, inclusive, will be initially described.

The furnace structure proper comprises side walls 2, end walls 3, a bottom wall 4 and a top 40 wall (not shown). An opening 5 is provided at one end of the furnace to permit material to enter the furnace. A discharge opening 6 having a door 7 thereon is provided at the other end of the furnace to permit material to be discharged 45 from the furnace after having passed therethrough. The furnace structure may be of any desired width or length, depending upon the use to which it is to be put and the size of the materials to be heated.

50 The material is placed in the furnace and is carried therethrough by means of a plurality of walking beams. The walking beam structure for conveying the material through the furnace comprises one series of longitudinally extending beams 8 which are supported for vertical reciprocatory motion, and a second series of walking beams 9 which are supported for horizontal longitudinal movement. The operation of these series of walking beams is so coordinated that the 55 vertically movable beams 8 are in their lowermost position during the period that the longitudinally movable beams are moving forward. During this period the material is supported by the longitudinally movable beams and is carried 60 forward thereby, the vertically movable beams in their lowermost position being below and out of contact with the material. After the forward stroke of the longitudinally movable beams has taken place, the vertically movable beams are 65 raised by appropriate mechanism, to be herein-after briefly described, and the material lifted from the longitudinally movable beams 9 and supported thereby. During the period that the material passing through the furnace is supported 70 by the vertically movable beams, the horizon-

tally movable beams are moved rearwardly so as to be ready to receive and again carry forward the material when the vertically movable beams are again lowered. In this manner the material is carried through the furnace in a step by step manner, the horizontally movable beams carrying the material forward through the furnace and the vertically movable beams supporting the material during the period that the horizontally movable beams are being returned to a position 10 to again advance the material through the furnace.

15 My invention is not limited to furnaces having walking beam structures of the character above described, as it may be embodied in structures utilizing an entirely different type of beam movement. It may be embodied in structures wherein a single series of movable beams are employed, which are movable in both a vertically extending direction and in a longitudinally extending direction, the material being supported on stationary beams or supports during the return stroke of the series of movable beams.

20 Extension arms 16 are provided and suitably connected to the longitudinally movable walking beams 9. The beams 9 or the extensions 16 extend through the charging opening of the furnace, and the extensions 16 are each provided with a rack 17 which cooperates with a gear 18 carried by a shaft 19 which is suitably driven 25 by a motor 20 through appropriate gear reducing mechanism 21. Through this mechanism the longitudinally movable beams will be reciprocated longitudinally forwardly and rearwardly 30 through the furnace. Driving mechanism of this 35 character is well known in the art and no further description thereof is deemed necessary.

40 The vertically movable beams 8 are suitably mounted on posts 22 extending through openings 23 in the furnace bottom. Each post 22 is provided with a rack 24 adjacent its lower end, which rack cooperates with a gear segment 25 mounted on a shaft 26 driven by suitable driving mechanism. The shaft 26 is rotated first in one 45 direction for raising the beams, and then in the reverse direction for lowering the beams to their lowermost position.

45 The walking beams 8 and 9 are each provided with horizontally extending material engaging fingers 27. These material engaging fingers are 50 located at spaced intervals along the length of each beam and the fingers on the beams 8 are spaced longitudinally of the furnace relative to the fingers 27 on the beams 8, so that they will be arranged in alternating relationship. The fingers 27 are of sufficient length to extend between the two adjacent fingers on each adjacent beam 55 so as to provide an overlapping relationship therebetween. This provides a highly desirable, supporting structure for the material. By reason 60 of a structure of this character, the material passing through the furnace will be well supported so that there will be little or no tendency whatever for the edges or corners of the material to bend downwardly during the heating operation, and particularly if it is necessary to maintain the material in the heating furnace for an appreciable period of time. Where it is necessary 65 to cease the movement of the material through the furnace for an appreciable period of time, the vertically movable beams can be raised so that the material engaging fingers 27 thereon will be in the same plane as the material engaging fingers on the longitudinally movable beams. 70 As can be readily seen, under such circumstances, 75

the material can be permitted to remain in the furnace for appreciable periods of time without any possibility of bending or warping of the edges or corners of the material.

5 The fingers 27 may be mounted on the beams 8 and 9 in any suitable manner. As shown in the drawings, each finger 27 has a horizontally extending portion 28 on each side thereof which is adapted to cooperate with retaining lugs 29 carried by the beam. These lugs are arranged on each side of each finger and hold them solid and prevent movement thereof longitudinally of the furnace.

Upstanding portions 35 are also carried by the 15 beams 8 and 9 between the fingers 27 for aiding in supporting the material. The top portion of each of these upstanding portions is substantially flush with the plane of the supporting surface of the fingers.

20 The vertically movable beams 8 are in the form of ordinary I-beams and are suitably mounted on plates 36 carried by the posts 22. The posts 22 for supporting the beams may be located at desired intervals throughout the length of the 25 furnace. I prefer to locate them sufficiently close together to prevent the beams from being subjected to stresses which might cause failure thereof under the heating conditions to which they will be subjected.

30 The horizontally movable beams 9 are substantially U-shaped in cross section and have horizontally extending projections 41 on the open end thereof. Each of the beams 8 and 9 may be rolled or cast as a single beam extending 35 throughout the length of the furnace, or they may be rolled or cast in sections and riveted together so that each beam will constitute a continuous beam extending throughout substantially the length of the furnace.

40 The beams 9 may be cast or, as will be pointed out hereinafter, formed from sheet metal. In the embodiment shown in Figures 1 and 2, the beams 9 are cast sections. Entirely satisfactory structures can, however, be made from sheet 45 metal. Where thin sheet metal is used it is desirable to provide further means to insure against warping or buckling of the beams.

The beams 9 are mounted in the furnace with the open ends thereof downwardly. Each beam 50 is supported at spaced intervals throughout the length of the furnace on wheels 42 which extend upwardly into the beam. Each wheel 42 is mounted on an axle 43 which is mounted on bearing plates 44 carried on the top of a pier 45. 55 The bearing plates 44 have upstanding portions 46 adjacent each end thereof adapted to cooperate with the axle 43 mounted thereon to prevent the wheel from being forced off the pier by the movement of the beam in a longitudinally 60 extending direction. The wheels 42 and the beam 9 mounted thereon are shown in the forward position in Figure 1. When the beam 9 is moved toward the charging end of the furnace by means of the apparatus described hereinbefore, the axles 43 of the wheels 42 will roll on the bearing plates toward the charging end of the furnace, and the beams 9 will roll along the periphery of each of the wheels 42. This 65 provides an anti-friction bearing for the longitudinally movable beams which is highly desirable. This arrangement also provides a continuous beam extending throughout the length of the furnace, and consequently results in a material reduction in the stresses to which the 70 beams themselves are subjected by reason of the

weight of the material being transported through the furnace.

As stated above, the wheels 42 extend into the U-shaped beams and cooperate with the sides thereof to prevent warping or buckling 5 thereof. The movement of the wheels 42 within the U-shaped beams prevents them from warping or buckling, and keeps them in proper alignment even though subjected to intense heat.

Cover plates 47 may be provided to prevent 10 scale or dirt from falling from the material being transported through the furnace onto the bearing plates carried by the piers 45. It is highly desirable to prevent scale and dirt from collecting in these bearing plates, as friction 15 between the axles 43 and their respective bearing plates would be enhanced thereby.

Where the furnace is of such length as to require the joining together of several beams in order to form a continuous beam extending substantially throughout the length of the furnace, suitable couplings or splicing members may be provided. In Figure 6 there is shown a coupling member 51 which may be securely fastened by rivets 52, or other suitable means, to adjacent sections of the longitudinally movable beams 9. In Figure 5 there is shown a coupling 53 which may be riveted or otherwise securely fastened to adjacent sections of the vertically movable beams 8.

As a further precaution against twisting or warping of the beams, I provide by my invention an intermediate pier or intermediate piers 10 positioned longitudinally of the furnace between the supports for the walking beams 8 and 9 heretofore described. Each intermediate pier 10 is provided with grooves 71 into which the beams 8 descend when lowered to their lowermost position. These grooves 71 have their upper side walls sloped as at 72, and as the beams 8 descend therein any tendency toward warping or bending is prevented. The beams 8 when in their lowermost position are arranged to rest on the bottom portions 73 of the grooves 71. This affords an additional support for the beams when 40 in lowered position.

Each intermediate pier 10 is also provided with grooves 74, each of which carries a bearing plate 75 on which a longitudinally reciprocable beam 9 rests. Each bearing plate 75 is provided with upstanding end portions 76 and an inner upstanding portion 77, these upstanding portions being adapted to cooperate with the lower ends of the beam 9 and prevent warping or bending thereof. The beams 9 at all times rest on the intermediate piers 10 and considerable of the weight of the beams, as well as of the material carried thereby, is carried by these intermediate piers. The stresses to which the beams 9 are subjected while transporting material through 55 the furnace are thereby materially reduced.

It will be readily apparent to those skilled in the art that the use of such piers intermediate the main supports and reciprocating parts for the beams is highly advantageous in a furnace 60 of this character, where the parts are subjected to high temperatures. The intermediate piers help support the weight of the beams and, in addition, the weight of the material carried thereby, thereby reducing the stresses to which 65 the continuous beams are subjected.

In the pack heating furnace shown in the drawings, discharging mechanism is provided adjacent the discharge end of the furnace for raising the material from the longitudinally ex- 70 75

tending beams and discharging it from the furnace. As will be noted from Figure 2, the longitudinally movable beams 9 extend beyond the ends of the vertically movable beams 8 adjacent to the discharge end of the furnace. On each side of the longitudinally movable beams 9 there is provided a pivotally mounted arm 54. These arms 54 are mounted on pivots 55 located on the outside of the end wall at the discharge end of the furnace, and the free ends thereof extend inwardly toward the center of the furnace. When in normal position the innermost ends of the arms 54 are located in a plane below the level of the material being transported through the furnace and are adapted to rest on one of the piers 45.

Driving mechanism is provided for raising and lowering the material discharging arms at proper times. As shown in the drawings, the driving mechanism comprises posts 57 carrying arm-engaging wheels or rollers at the upper ends thereof for engagement with the arms 54. The posts are provided with racks 56 adjacent the lower ends thereof which are adapted to cooperate with gears 58 carried by a shaft 26' adapted to be driven by the same driving element as the shafts 26 so as to synchronize the movement of the discharging arms with the movement of the vertically movable beams 8. When the beams 8 are in their lowermost position, the arms 54 will be in the position shown in full lines in Figure 1. When raised to the level of the longitudinally movable beams the discharging arms will also be raised to the level of the longitudinally movable beams, and when the vertically movable beams 8 are in uppermost position the arms 54 will be raised to the position shown in chain lines in Figure 1. Of course, the stroke of the posts 57 will be considerably larger than the stroke of posts 22 but the parts can readily be arranged to accomplish this.

Each arm 54 is provided with a plurality of rollers 60. Each roller 60 is mounted on a short spindle 61 which is adapted to cooperate at either end thereof with a bearing groove or recess 62 formed in the arm 54. The bearing grooves or recesses 62 are elongated in shape and permit the rollers to move lengthwise of the arms. When the arms 54 are in lowered position, as shown in solid lines in Figure 1, the rollers 60 will assume positions at the lowermost ends of the grooves 62, as shown in solid lines in Figure 1. As the arms 54 are raised, a sheet or other material will be picked up by the rollers from the beams 9, and as the arms 54 continue in an upward direction beyond the horizontal, the rollers 60 with the material thereon will move rapidly forwardly toward the discharge end of the furnace and the material carried by the rollers will be given an appreciable impetus toward the discharge opening. The material will then continue toward the discharge end of the furnace and will roll on the rollers which have assumed a position such as indicated in dotted lines in Figure 1.

The advantages of such a structure as that described above will be apparent to those skilled in the art and need not be specifically pointed out herein. The walking beam structure is of such character as to permit suitably rapid passage of the material through the furnace and to provide adequate support for the material at all times while in the furnace. It is also of such character as to prevent buckling or warping of the parts which are subjected to excessive heat, and is of such character that the quantity of al-

loy steel required will be materially reduced. It will also be apparent to those skilled in the art that the stresses and strains on the beams are minimized by the construction which I provide.

In Figure 8 of the drawings, I have shown a modification of one feature of my invention. In this embodiment the longitudinally movable beam 80 may be made from relatively thin sheet material and formed into the U-shaped beam shown. I have found that a beam such as that shown in Figure 8 will be entirely satisfactory when formed of thin sheet material rather than cast. I prefer to use sheet metal of approximately $\frac{1}{8}$ inch in thickness for the portions of the beams located in the hotter zones of the furnace, and sheet metal approximately $\frac{1}{4}$ inch in thickness for the portions of the beams located in the cooler zones of the furnace.

The beam 80 is shown as provided with a material supporting and engaging finger 81, such as the material supporting and engaging fingers 27 of the embodiment heretofore described. The beam 80 is shown as cooperating with a wheel 82 mounted on an axle 83 which is mounted on castings 84 forming bearing plates for the axle 83. The wheel 82 extends upwardly into the U-shaped beam 80 and will prevent collapse or warping of the beam. Each casting 84 is provided with a horizontally extending portion 85 extending over the bearing plates of the casting, and one end of the axle 83 so as to provide a shield therefor. Each casting 84 is also provided with an upwardly projecting portion 86, extending upwardly from the horizontally extending portion 85, which has a curved plate 87 mounted at its upper end adapted to extend over the openings 88 between the U-shaped beam and the casting for the purpose of preventing scale and dirt from obtaining access to the bearing plate of the casting. These upstanding portions 86 are located adjacent the ends of the U-shaped beam 80 and are adapted to cooperate therewith and prevent the warping or twisting of the beams.

Suitable braces or reenforcing members 89 are also provided for reenforcing the beam 80 at spaced intervals throughout the length of the furnace. I prefer to form these braces integral with the material engaging fingers 81.

In Figure 9 I have shown a further modification of one feature of my invention, wherein upstanding portions 90 are provided on each portion of the axle 91 of the wheel 92 adapted to support the longitudinally movable beam 93. These upstanding portions 90 are adapted to cooperate with the ends 94 of the beam 93 and prevent warping or twisting of the beam. In this embodiment each portion of the axle 91 of the wheel 92 is mounted on a bearing plate 95 carried by a suitable pier or pedestal in the furnace.

The wheel 92 shown in this figure and also in Figure 10 is especially designed for the purpose of taking care of expansion and contraction due to the heat of the furnace. The wheel is provided with a plurality of spokes 96 which are formed integrally with the periphery of the wheel at the outer ends thereof, and are turned inwardly in opposite directions adjacent their inner ends; that is, the inner ends of adjacent spokes are turned in opposite directions. At their inner ends they are made integral with the adjacent portion of the axle 91, which comprises two hollow castings, as shown in the drawings.

A wheel of this character is highly desirable in that it takes care of expansion and contraction thereof occasioned by the heating and the

cooling of the furnace, thereby eliminating break downs at this point in the furnace structure.

In Figures 14, 15 and 17, I have shown a further modification of my invention. In this embodiment of my invention the longitudinally movable beams 100 and the vertically movable beams 101 are both formed of sheet metal. Each beam 100 is U-shaped and is adapted to receive and be supported by a wheel 102 mounted on an axle 103, each end of which is adapted to cooperate with a casting 104 having a bearing plate 105 on which the axle rolls. A casting 104 is mounted on each side of each wheel 102 on a pier 106. Openings 107 are, of course, provided in the pier to receive the wheels 102. Each casting 104 is provided with an upwardly extending portion 108 adapted to cooperate with the adjacent side of the adjacent beam 100 to prevent warping thereof. Scraping plates 109 are provided on these upstanding portions to prevent scale from collecting on the horizontally disposed portions 110 of each beam 100. Material engaging and supporting fingers 111 are mounted on each beam 100 at spaced intervals throughout the length of the furnace for supporting the material being carried therethrough. Each finger 111 has downwardly extending braces 112 extending downwardly over the beam 100 on each side thereof to make the beam more rigid and prevent buckling or warping thereof.

Each vertically movable beam 101 is formed in substantially U-shape from sheet metal. Each beam 101 is formed somewhat differently than each longitudinally movable beam in that they have no horizontally extending projections on the ends thereof. Each beam 101 is provided with a U-shaped bracket 113 extending longitudinally thereof and secured thereto. These brackets 113 are provided for the purpose of preventing the beams 101 from buckling or warping inwardly. Each beam 101 is mounted on a plurality of vertically movable posts 114 spaced throughout the length of the furnace. These posts 114 are provided with upwardly extending flanges 115 adapted to extend upwardly along the outer edges of the beam 101 for maintaining the beams on the posts and for aiding in preventing buckling thereof.

Each beam 101 is provided with a plurality of material engaging fingers 116 spaced throughout the length of the furnace. These fingers 116, similarly to the fingers 111, have downwardly extending braces 118 extending downwardly along the outer surfaces of the beams for the purpose of increasing the rigidity thereof and for preventing buckling and warping.

In Figures 16, 18, 19 and 20, I have shown a still further modification of my invention. In this embodiment there is provided a series of longitudinally movable beams 120 and a series of vertically movable beams 121. The longitudinally movable beams 120 are substantially similar to the longitudinally movable beams 100 shown in Figure 14, except that they are not provided with material engaging fingers such as those mounted on longitudinally movable beams 100. In this embodiment of the invention, the axles 122 of the wheels 123 cooperate with and rest in castings 124 mounted on the pier 125. These castings 124 are provided with upwardly extending projections 126 adapted to cooperate with the beams 121 adjacent thereto for preventing buckling or warping thereof. The castings 124 are also provided with upstanding portions 127 adapted to cooperate with the horizontally dis-

posed edges of the beams 120 to prevent outward displacement thereof due to the heat of the furnace.

In this embodiment of the invention caps or castings 130 may be provided on the intermediate piers for aiding in maintaining the longitudinally movable beams in proper alignment and for preventing buckling or warping thereof. These caps or castings 130 are provided with upstanding portions 131, one side of which is adapted to cooperate with the horizontally extending portions of the adjacent beam 120 and the other side of which is adapted to cooperate with the adjacent beam 121 to maintain it in proper alignment and prevent warping or buckling thereof. Lugs 132 are also provided on each cap or casting 130 to prevent collapsing of the beams 120.

As will be readily apparent from the above description, I provide a walking beam structure in which the beams may be made of thin sheet metal and wherein such beams may be maintained rigid and warping or buckling thereof entirely prevented. The structure which I provide is rigid and will not be destroyed or the operation thereof impaired by the high temperatures to which furnaces of this character are subjected in operation.

Another feature of my invention not heretofore discussed resides in the provision of a structure wherein the material passing through the furnace may be supported by all of the material engaging and supporting mechanism during the period or periods that the material is held in the furnace by reason of delays or during the period or periods that the material moving mechanism remains stationary. In the embodiments shown in the drawings, the vertically movable beams during such periods are raised so that the material engaging and supporting fingers carried thereby are at the same level as those carried by the longitudinally movable beams. This affords additional support to the material in the furnace and prevents bending thereof as the material is adequately supported at all points.

In the foregoing specification, I have described my invention as relating generally to heating furnaces, and more particularly to heating furnaces used for metallurgical purposes. My invention is not limited to heating furnaces for metallurgical purposes but relates to heating furnaces of any character whatsoever wherein the material to be treated is conveyed through the furnace at such a rate of travel as to enable the material to be properly heated and treated by the time it reaches the delivery or discharge end of the furnace. It is equally applicable to glass annealing leers, as well as metallurgical furnaces, and the term "heating furnace" as used in the specification and claims hereof includes annealing leers and the like, as well as metallurgical furnaces.

While I have shown and described several embodiments of my invention, it will be understood that I do not intend to be limited thereby, and that my invention may be otherwise embodied within the scope of the appended claims.

I claim:

1. In a continuous heating furnace, means for moving material through the furnace comprising a series of spaced longitudinally extending inverted U-shaped beams, means for reciprocating said beams in a longitudinally extending direction, means including a plurality of wheels extending upwardly into said beams for supporting

them and adapted to prevent warping or twisting thereof, supports for said wheels, and means arranged between said spaced beams for supporting the material during the return stroke of said reciprocating beams, the sides of said U-shaped beams terminating in outwardly extending flanges which cooperate with said wheel supports.

2. In a continuous heating furnace, means for moving material through the furnace comprising 10 a series of longitudinally extending spaced beams, means for moving said beams substantially simultaneously in a vertically extending direction, a second series of longitudinally extending spaced U-shaped beams arranged in alternating relationship relative to said vertically movable beams, the sides of said U-shaped beams terminating in outwardly extending flanges, means for moving said second series of beams in a longitudinally extending direction, antifriction supports for supporting and aligning said longitudinally movable beams, said supports having a portion extending into said U-shaped beams for preventing warping or twisting thereof.

3. In a continuous heating furnace, means for 25 moving material through the furnace comprising a longitudinally extending beam in the form of an inverted channel, means including a plurality of wheels extending upwardly into said channel for supporting said beam and adapted to prevent warping or twisting thereof, supports for said wheels, and means for moving said beam in a longitudinally extending direction, the sides of said channel terminating in outwardly extending flanges which cooperate with said wheel supports.

35 4. In a continuous heating furnace, means for moving material through the furnace comprising a longitudinally extending beam in the form of an inverted channel, the sides thereof terminating in outwardly extending flanges, means for supporting said beam including means extending upwardly into the beam to prevent warping or twisting thereof, and means for moving said beam in a longitudinally extending direction, the beam supporting means being adapted to cooperate 40 with the flanges of said channel.

5. In a continuous heating furnace, means for moving material through the furnace comprising 50 a series of spaced longitudinally extending U-shaped beams, the sides thereof terminating in outwardly extending flanges, means for reciprocating said beams in a longitudinally extending direction, a plurality of horizontally extending material engaging and supporting fingers carried by at least one of said beams, said fingers being spaced longitudinally of the furnace, vertically movable means arranged between said spaced beams for supporting the material during the return stroke of said beams, and a plurality of horizontally extending material engaging and 55 supporting fingers carried by said means, said fingers being spaced longitudinally of the furnace and being arranged in alternating relationship relative to the material supporting fingers carried by said beams.

65 6. In a continuous heating furnace, means for moving material through the furnace comprising a longitudinally extending beam in the form of an inverted channel, the sides thereof terminating in outwardly extending flanges supporting 70 means for said beam including a bearing plate, a wheel having an axle thereon cooperating with said bearing plate, said wheel extending upwardly into said channel for supporting the same and adapted to prevent warping or twisting thereof, 75 means carried by said bearing plate for cooperat-

ing with said beam flanges to prevent warping or twisting thereof, and means for moving said beam in a longitudinally extending direction.

7. In a continuous heating furnace, means for moving material through the furnace comprising 5 a longitudinally extending U-shaped beam formed of sheet metal and adapted to support the material, the sides of the beam terminating in outwardly extending flanges, means including a wheel and axle for supporting said beam, said wheel extending into the U-shaped beam to prevent buckling or warping thereof, means for imparting a reciprocatory motion to said beam, and means for supporting the material during the return stroke of said reciprocating beam.

8. In a continuous heating furnace, means for moving material through the furnace comprising 10 a plurality of longitudinally extending beams, means for supporting said beams for reciprocatory motion, a pier intermediate said supports having recesses therein to receive said beams and adapted to prevent warping or twisting thereof, means for imparting a reciprocatory motion to said beams, and means for supporting the material during the return stroke of said reciprocating beam 15 said beam said supporting means being movable vertically from a position where it is supported by said pier to a position where it supports the movable material.

9. In a continuous heating furnace, a series of 20 spaced longitudinally extending beams, means for supporting said beams and for moving them in a vertically extending direction, a second series of longitudinally extending beams arranged in alternating relationship relative to said vertically 25 movable beams, means for supporting and for moving said second series of beams in a longitudinally extending direction, and a pier intermediate the aforesaid supports having recesses 30 therein adapted to receive said longitudinally movable beams and prevent warping or twisting thereof and to support the first series of beams 35 and prevent warping or twisting thereof.

10. In a continuous heating furnace, a series 40 of spaced longitudinally extending beams, means for supporting said beams and for moving them in a vertically extending direction, a second series 45 of longitudinally extending beams arranged in alternating relationship relative to said vertically movable beams, means for supporting said second series of beams and for moving them in a longitudinally extending direction, and a pier intermediate the aforesaid supports having recesses 50 therein adapted to receive the longitudinally movable beams and prevent warping or twisting thereof, said recesses being provided with bearing plates on which the longitudinally movable beams 55 may slide and which prevent warping or twisting thereof.

11. In a continuous heating furnace, means for 60 moving material through the furnace comprising a series of spaced longitudinally extending U-shaped beams, the sides thereof terminating in outwardly extending flanges, means for reciprocating said beams forwardly and rearwardly 65 through said furnace, a plurality of horizontally extending material engaging and supporting fingers carried by at least one of said beams, said material engaging and supporting fingers having vertically extending braces attached thereto and 70 adapted to brace the beam against twisting or warping, and means arranged between said spaced beams for supporting the material during the rearward stroke of said beams.

12. In a continuous high temperature furnace 75

for heat treating metallic material, means for moving the material through the furnace including a plurality of longitudinally extending inverted channel beams, each of said beams comprising a bearing surface and flanges extending downwardly therefrom, antifriction members spaced longitudinally of said beams, extending into said channels between said flanges and engaging said bearings for supporting said beams and for preventing warping of said flanges, and means for reciprocating said beam on said anti-friction members.

13. In a continuous high temperature furnace for heat treating metallic material, means for moving the material through the furnace including a plurality of longitudinally extending inverted channel beams, each of said beams comprising a bearing surface and flanges extending downwardly therefrom, a plurality of wheels extending 20 into the channels of each beam between the flanges thereof and engaging said bearing for supporting said beam and for preventing said

flanges from bending inwardly, means extending alongside of said beam for preventing said flanges from bending outwardly, and means for reciprocating said beams on said wheels.

14. In a continuous heating furnace, means for moving material through the furnace, comprising a longitudinally extending beam in the form of an inverted channel of comparatively thin cross-section, the sides thereof terminating in outwardly extending flanges, supporting means for said beam including a bearing plate, a wheel having an axle thereon cooperating with said bearing plate, said wheel extending upwardly into said channel for supporting the same and adapted to prevent warping thereof, means carried by said bearing plate for cooperating with said beam flanges to prevent warping of the beam, means for moving said beam in a longitudinally extending direction, and a plurality of horizontally disposed material engaging fingers on said beam. 10 15 20
